The characteristic feature of the design resides in the appearance of the particular decorative pattern on the inner and outer surfaces of the feeding bowl.

We claim:

The ornamental design for a feeding bowl for pets, as shown and described.
